AUTOMATIC OILER

Oluf F. Jensen, Council Bluffs, Iowa

Application April 20, 1936, Serial No. 75,360

6 Claims. (Cl. 184—52)

The principal object of my invention is to provide an automatic oiler for devices having pressure pulsations such as the steam valve and cylinder of a steam engine.

5 A further object of this invention is to provide an automatic oiler that is easily installed and when once installed requires no further attention outside of servicing it with additional oil when the oil is depleted.

10 A still further object of this invention is to provide an automatic oiler that may be easily adjusted for furnishing more or less oil over a given period of operation.

These and other objects will be apparent to 15 those skilled in the art.

My invention consists in the construction, arrangement and combination of the various parts of the device, whereby the objects contemplated are attained as hereinafter more fully set forth, 20 pointed out in my claims and illustrated in the accompanying drawing, in which:

Fig. 1 is a side sectional view of my device ready for use.

Fig. 2 is a top plan view of my automatic oiler. 25 Fig. 3 is an enlarged side sectional view of the oil regulator valve.

One of the hardest mechanisms to oil and keep oiled are those mechanisms wherein an intermittent fluctuating pressure is experienced.

30 A case in point is the steam valve and piston of a steam engine working under varying load and speed conditions. Obviously any attempt to force oil into a chamber having steam pressure is most difficult as it seriously affects, not only 35 the injection of the oil into the chamber and working parts, but makes such introduction of oil questionable and not uniform. I have overcome this by providing an oiler that successfully operates by virtue of the pulsation of pressure leading 40 to parts to be lubricated, such as exists between the throttle valve and main valve of a steam engine.

45 Referring to the drawing, I have used the numeral 10 to designate the enclosed housing of my oiler. This housing has a hollow stem portion, 11, extending completely through it, as shown in Fig. 1. The lower end of this stem portion 11 is threaded and designed to be screwed into the wall of the steam pipe or valve chamber 50 leading to the parts to be oiled. Obviously the inside of this stem portion 11 must communicate with the inside of the cylinder or like to be oiled. The numeral 13 designates a block portion formed on top of the housing 10. This block portion 13 55 has a vertical passageway 14 extending com-

pletely through it and communicating with the inside of the housing 10. The numeral 15 designates a screw cap for detachably closing the upper top open end of the passageway 14. Also threaded in this passageway 14 and normally resting under the closing cap 15 is the oil regulating valve. This oil regulating valve has a casing of two parts which I have designated by the numerals 16 and 17, as shown in Fig. 3. These two sections 16 and 17 are threaded together and to all intents and purposes form a single valve casing having the vertical passageway 18 extending completely through it. Inside this valve casing is an enlarged compartment 19 having both of its ends communicating with a 15 passageway 18, as shown in Fig. 3. This enlarged compartment 19 provides space for the operation and reciprocation of movable portion 20 of the valve and has both of its ends beveled or conical as shown in Fig. 3, to provide valve seats in both 20 directions. The movable portion of the valve 20 is pointed at both of its ends in order that when it is moved upwardly it will seat at the upper valve seat in the enlarged chamber 19, and when it is moved downwardly it will seat in the lower 25 seat of the enlarged compartment 19, thereby closing the passageway 18 by movement in either direction. This member 20 has a diameter less than the inside diameter of the enlarged compartment 19, and is permitted a certain amount 30 of longitudinal reciprocation, as shown in Fig. 3. The numeral 21 designates a stem secured to the lower end of the member 20 and extending downwardly into the passageway 14 through the passageway 18. The numeral 22 designates a nut 35 threaded onto or otherwise secured to the lower end portion of the stem 21. The numeral 23 designates a coil spring embracing the stem 21 and having one of its ends engaging the nut 22, and its other end engaging the member 17, as is 40 shown in Fig. 3, for yieldingly holding the member 20 in engagement with the lower seat of the enlarged compartment 19. The numeral 24 designates a passageway in the block 13, having one end communicating with the inside of the passageway 45 of the stem 11 and its other end communicating with the passageway 14 above the oil regulating valve and below the cap 15, as shown in Fig. 1.

The numeral 25 designates a hollow stem extending downwardly in the housing 10 and terminating near the bottom of the housing 10. The passageway of this hollow stem 25 communicates with the bottom of the housing 10 and the outside top of the housing 10. The numeral 26 design- 55

nates a fixed valve seat in the upper portion of the passageway of the stem 25. The numeral 27 designates a detachable plate rigidly secured on top of the housing 10 and over the passageway 5 of the stem 25.

The under side of this plate 27 has a slight depression for receiving the central portion of the diaphragm element 28. This diaphragm plate 28 is rigidly secured at its marginal edge 10 by being clamped between the peripheral edge of the plate 27 and the top of the housing 10, thereby closing the passageway of the stem 25 to the outside atmosphere. The numeral 29 designates a movable valve portion rigidly secured 15 on the bottom of the diaphragm plate 28, and capable of seating in the valve seat 26, for closing the passageway in the stem 25. The numeral 30 designates a coil spring having its upper end 20 engaging the plate 27 and its lower end engaging the top of the diaphragm for yieldingly holding the valve member 29 seated in the valve seat 26. The numeral 31 designates a hollow dome member threaded on to the upper end portion of the stem 11 and communicating with the inside of 25 the passageway of the stem 11 the upper end of the stem 11 terminating near the inside top of the dome as shown in Fig. 1. The numeral 32 designates a second passageway in the stem 11 communicating with the inside bottom of the 30 dome. The numeral 33 designates a passageway in the top portion of the housing 10, having one end communicating with the passageway 32 and its other end communicating with the outside top of the housing 10 at a point under the diaphragm 35 34. The numeral 34 designates a filling plug 28. The numeral 35 designates a drain plug threaded into the bottom of the housing 10.

The practical operation of the device is as 40 follows: After my automatic oiler has been installed and filled with oil, when the steam valve or throttle is opened to start the engine, steam will pass upwardly through the stem 11 and into the dome 31. It is possible that this steam will 45 be condensed inside the dome, but at any rate the condensed steam or steam will pass downwardly through the passageway 32 into the passageway 33 and to a position under the diaphragm 28, thereby raising it against the action of the spring 30.

With the diaphragm 28 in an upper position 50 the movable valve element 29 will be off of its seat and the steam or condensate will pass downwardly through the stem 25 to the bottom of the housing 10, where all of it then is reduced to liquid. As this condensate will be water the oil in the housing 10 will be supported by the water and will be forced into the passageway 14 with a slightly greater pressure on the bottom side of 60 the valve element 20 than on the top side owing to the weight of the water in condensing dome or passageway 32. It is obvious that when the steam valve opens the steam port to the engine cylinder there will be a momentary reduction in pressure in the valve chamber 12 and inside the stem 11 and the pressure of the oil in the passageway 14 will be momentarily greater than that in the passageway 24, thereby permitting the spring 23 to compress, allowing the valve element 20 to 70 move upwardly to seat in the upper end of the compartment 19. In other words, every backward and forward movement of the piston will cause a pulsation of pressure inside the device and thereby reciprocating the valve element 20 and 75 permitting very small amounts of oil to pass by

the reciprocating valve element 20 and into the passageway 24. This oil will naturally find its way into the stem 11 and flow down into the cylinder 12. It will be noted that the valve 20 operates to conform with the pulsating pressure 5 that intermittently exists in the passageway 24. Due to the close fit and short movement of the member 20 the oil fed into the cylinder will be a very small amount. Obviously, the amount of oil fed into the cylinder will depend on the relative diameters of the member 20 and the inside 10 of the compartment 19 and also the distance of the movement of the member 20. Therefore the amount of oil to be fed may be predetermined 15 by the size of the unit used. They may be made in various sizes and be changed at will by removing cap screw 15.

It will also be noted that when the steam throttle is closed and no pressure exists inside the stem 11, water can not be forced upwardly 20 through the stem 25 and into the stem 11 by existing pressure because of the diaphragm 28 which moves downwardly to close the passageway in the stem 25 when the pressure is relieved from the under side of the diaphragm. From this it 25 will be seen that as the device uses oil a proportionate amount of condensate will be placed in the bottom of the device and all of the oil will be used before the water reaches the passageway 14. Obviously when the device has had all of 30 the oil in it depleted it will be completely filled with water. The purpose of diaphragm 28, valve 29 and spring 30 is to retain oil in housing 10 when the throttle valve is closed. Were it not for that the hot oil would expand when relieved 35 of pressure and find its way out through hollow stem 11 and into the engine where it would boil when relieved of pressure. To replenish the device with oil the member 35 would be removed to drain the water from the device, after which 40 the member 35 is replaced and the member 34 removed in order to refill the device with oil. After oil has been replaced in the device the member 34 is screwed back into place.

Some changes may be made in the construction 45 and arrangement of my improved automatic oiler without departing from the real spirit and purpose of my invention, and it is my intention to cover by my claims any modified forms of structure or use of mechanical equivalents 50 which may be reasonably included within their scope.

I claim:

1. In a device of the class described, a housing 55 designed to contain oil, a conduit having one of its ends communicating with the bottom of said housing and its other end in communication with a fluid supplied under alternating pressures, an oil conduit having one end communicating with the top of said housing and its other end communicating with the inside of said first mentioned conduit, a diaphragm operated valve imposed in said first mentioned conduit for closing said conduit to the inside of said housing when a reduction of pressure is experienced inside said 65 first mentioned conduit, and a movable valve mechanism imposed in said last mentioned conduit.

2. In a device of the class described, a housing 70 designed to contain an oil, a conduit having one end designed to be in communication with a fluid supplied under alternating pressure and its other end in communicating with the bottom of said housing, an oil conduit having one end communicating with the inside top of said housing and its 75

- other end communicating with the inside of said first mentioned conduit, a diaphragm operated valve imposed in said first mentioned conduit for closing said conduit to the inside of said housing 5 when a reduction of fluid pressure is experienced inside said first mentioned conduit, and a two way valve mechanism imposed in said last mentioned conduit.
3. In a device of the class described, a housing 10 designed to contain an oil, a conduit having one end designed to be in communication with a fluid supplied under alternating pressure and its other end communicating with the inside bottom of said housing, an oil conduit having one end communicating with the inside top of said housing and its other end communicating with the inside of said first mentioned conduit, a diaphragm operated valve imposed in said first mentioned conduit for closing said conduit to the inside of 15 said housing when a reduction of fluid pressure is experienced inside said first mentioned conduit, two opposed valve seats in said second mentioned conduit, and a reciprocating valve element between said two valve seats capable of engaging either of said valve seats for closing said second mentioned conduit at times.
4. In a device of the class described, a housing 20 designed to contain an oil, a conduit having one end designed to be in communication with a fluid supplied under alternating pressure and its other end communicating with the bottom of said housing, an oil conduit having one end communicating with the inside top of said housing and its other end communicating with the inside of said first mentioned conduit, a diaphragm operated valve imposed in said first mentioned conduit for closing said conduit to the inside of said housing when a reduction of fluid pressure is experienced inside said first mentioned conduit, two opposed 25 valve seats in said second mentioned conduit, a reciprocating valve element between said two

valve seats capable of engaging either of said valve seats for closing said second mentioned conduit at times, and a means for yieldingly holding said reciprocating valve element in one direction.

5. In an automatic oiler, a housing designed to contain an oil, a hollow vertical stem secured to said housing and designed to have its lower end in communication with a fluid supplied under alternating pressure, a block portion on said housing having a passageway in communication with the inside of said hollow stem and the inside top of said housing, a two-way reciprocating valve mechanism imposed in said passageway, a hollow vertical stem extending downwardly into said 15 housing and terminating near the bottom of said housing, a diaphragm secured to the top of said housing and over said last mentioned hollow vertical stem, a valve member on said diaphragm capable of closing the passageway of said last 20 mentioned hollow stem, a closed dome element communicating with the inside top of said first mentioned hollow stem, and a passageway having one end communicating with the inside of said dome element and its other end communicating 25 with the under side of said diaphragm.

6. In a device of the class described, a housing 30 designed to contain an oil, a conduit having one end designed to be in communication with a fluid supplied under alternating pressure and its other end communicating with the inside bottom of said housing, an oil conduit having one end communicating with the inside top of said housing and its other end operatively communicating with said alternating fluid pressure, a diaphragm operated 35 valve imposed in said first mentioned conduit for closing said conduit to the inside of said housing when a reduction of the pressure is experienced inside said first mentioned conduit, and a movable valve mechanism in said oil conduit. 40

OLUF F. JENSEN.
